UNITED STATES PATENT OFFICE.

ANGUS BEATON, OF VULCAN, ALBERTA, CANADA.

DRAFT EQUALIZER.

Application filed February 4, 1922. Serial No. 534,230.

To all whom it may concern:

Be it known that I, ANGUS BEATON, of the town of Vulcan, in the Province of Alberta and Dominion of Canada, have invented certain new and useful Improvements in Draft Equalizers, of which the following is a specification.

This invention relates to draft equalizers, and more particularly to a device which is intended for use when there are two or more horses in the lead and which will equalize the draft on all the horses.

It also has for one of its objects to provide a device which will lower the draft on the pole team, remove any pressure from the back bands and belly bands on the horses forming the pole team and which will lower the traces of the pole team thereby preventing any rubbing of these members against the sides of the horses forming the pole team.

Further objects are to make a direct draft from the lead team or teams to the wagon to which the pole team is hitched, to eliminate lead rods and whiffletrees for the lead teams, to provide a device that is simple and not liable to go out of repair, and generally to adapt the several parts to better perform the functions required of them.

The invention consists essentially of the improved construction particularly described in the following specification and accompanying drawings forming part of the same and set forth in the appended claim.

In the drawings:

Figure 1 is a perspective view of my improved draft equalizer.

Figure 2 is a plan view of the same.

Figure 3 is a transverse sectional view through the main tug.

Figure 4 is a fragmentary view of a hame, showing the means used for connecting of the improved equalizer thereto.

Figure 5 is a plan view of the equalizing member.

Referring to the drawings:

A indicates a metal tug or connecting element preferably made of steel, having at one end means to connect with the equalizing bar B and at the other, means to connect with a strap or bar C which extends to the hame. Means to connect with the equalizing bar B include parallel spaced plates 10 and 11 supporting a pin 12 between them which is pivotally connected to the equalizing bar B as by engaging in an open eye 13 at one

end of the same. Above the plates 10 and 11 an eye or loop 14 is provided to receive the backband of the horse, while at the bottom of the plate 10 an offset and inclined 60 loop or eye 15 is provided adapted to engage with the belly band of the horse.

The equalizing bar B is made of strong and durable steel and is curved or inclined from one end to the other as shown, being 65 provided intermediate of its length with a pivoted shackle 16 which, if desired, may be replaced by a perforation or eye in the equalizing bar itself and a plurality of spaced orifices 17 and 18 on the end of the 70 bar remote from the eye 13. The shackle 16 is designed to be connected to a suitable hook or tug 19 on the trace 23 which leads to a whiffletree D, (see Figure 2).

The connection between the tug A and the 75 member C comprises a U-shaped member 24 having a pivoted pin 25 which extends through a looped end of the member C, the opposite end of the member embracing a pivot pin 26 supported in lugs 27 connected 80 to the hame E. The lower bracket 26 is formed with an extension lug 28 carrying a ring 29 from which depends a strap 30 which may be conveniently connected to the front team and which is connected at its 85 opposite end to the equalizing bar B as hereinafter described.

In using the invention, a trace 23 is hitched to the shackle 16 and to the whiffletree D of the wagon, as shown in Figure 2. 90 Should a second team of horses be employed in front of the pole team, the shackle 16 thereof is removed to the orifice 17 immediately over that engaging the trace 31, and any unemployed remaining orifices are used 95 in a similar way if there are more horses pulling the load.

When several teams of horses are pulling a wagon, the pole team is usually the one making the first pull forward and, on such 100 a movement, the curved arm or equalizer will be drawn backward which will tighten the traces of the front horses hitched to the equalizing bar B.

It will thus be seen that the front horses 105 on their first move forward will operate a direct pull on the lead as well as the pole horses, through the medium of the equalizing bar B.

As many changes could be made in the 110 above construction and many apparently widely different embodiments of my invention

tion within the scope of the claim, constructed without departing from the spirit or scope thereof, it is intended that all matter contained in the accompanying specification and drawings shall be interpreted as illustrative and not in a limiting sense.

What I claim as my invention is:

A draft equalizer comprising a body portion having a central section, spaced integral plates on one side of the central section, a connecting pin between said plates, one of the plates having an offset inclined eye integral therewith, a U-shaped member formed integral with the body portion on the opposite side to that on which the plates are formed, a pivot pin mounted in the said

U-shaped member, a tug having an end extending around the pin, means for connecting the opposite ends of the tug to a hame, an equalizing bar having an open eye by 20 which it may be connected to the pin between the spaced plates, means at the other end of said equalizing bar to receive a trace end and a shackle mounted on the bar intermediate of its length adapted to receive a 25 trace end.

In witness whereof I have hereunto set my hand in the presence of two witnesses.

ANGUS BEATON.

Witnesses:

ALFRED E. CAMPBELL,
GRACE W. SISIUS.
